UNITED STATES PATENT OFFICE.

CHARLES SCHEIDEN, OF DENVER, COLORADO.

TRACK-CLEANER.

1,147,122.

Specification of Letters Patent. Patented July 20, 1915.

Application filed December 27, 1913. Serial No. 809,020.

To all whom it may concern:

Be it known that I, CHARLES SCHEIDEN, a citizen of the United States, residing in the city and county of Denver and State of Colorado, have invented certain new and useful Improvements in Track-Cleaners; and I do hereby declare the following to be a full, clear, and exact description of the invention, such as will enable others skilled in the art to which it appertains to make and use the same.

This invention relates to improvements in means for clearing a roadway through snow, and while it is especially designed for the purpose of clearing street railway and steam railroad tracks, it may be also used to open up a plain roadway by the employment of suitable propulsion means, such as a gasolene motor or other engine. For the purpose of simplicity of illustration, however, I am simply describing my invention as being applied to the use of clearing street railway tracks during heavy snow storms, wherein the power applied for driving my machine is obtained through a suitable trolley (not shown) completing an electric circuit between a trolley wire and an electric motor mounted on a truck forming a part of the improved track cleaner.

Collectively speaking, the main object of the invention consists in the employment of a particular form of shovel extending transversely of the track or path to be cleared, and coöperating with a suitable conveyer for discharging the shoveled snow to one side of the track, and which conveyer may be swung around in substantially the longitudinal plane of its supporting truck, to enable the machine to be properly housed when not in use, without taking up too much room.

Another object of the invention is to employ a rotary brush in combination with the shovel and conveyer to sweep the track clean of snow when the greater quantity of snow has been shoveled off and conveyed and dumped a substantial distance to one side of the track or roadway being opened. By my invention, and by having the conveyer inclining upwardly at a proper angle, means are provided for effectively shoveling away snow of practically any depth.

Another object of the invention is the provision of a machine that is powerful and effective in action, but which is comparatively cheap to construct and operate, and

which at the same time is very simple, strong and durable in structure, preventing the same from readily getting out of order.

With these principal and other objects in view, the invention, therefore, consists of the novel arrangement and combination of parts, which will more fully appear from the following description, and the essential features of novelty will be more particularly and succinctly pointed out in the appended claims. It will be obvious, however, that minor structural equivalents may be employed without departing from the spirit of the invention, and without sacrificing any of the vital principles thereof, and while the invention is not limited, therefore, to the exact details shown and described, still for the purpose of disclosure reference is had to the accompanying drawings illustrating a practical embodiment of the same, in which drawings like characters designate the same parts in the several views, and in which:—

Figure 1 is a view in plan of my improved machine, a part of the conveyer casing being broken away to show the discharge end of the shovel, and the conveyer being also shown, in dotted lines, in the position to which it may be swung when the machine is housed. Fig. 2 is a view in side elevation, partly broken away to show the horizontal portion of the shovel relatively to the inclining portion, and showing in section a stirrup mounted on each side of the truck for jacking the inner ends of braces or supporting plates for the front of the shovel. Fig. 3 is a view in front elevation, the conveyer and truck being shown in dotted lines. Fig. 4 is a vertical cross sectional view on the line 4—4 of Fig. 1. Fig. 5 is a transverse vertical cross sectional view on the line 5—5 of Fig. 4; and Fig. 6 is a detail cross sectional view on the line 6—6 of Fig. 2.

Any suitable vehicle or support may be employed in carrying out my invention, but in the drawings I have simply shown a truck comprising the framework 1, wheels 2 and supporting any suitable motor or engine, shown conventionally in the drawings as comprising an electric motor 3, which receives its current from a trolley and trolley wire, not shown, although, as before stated, any suitable form of propulsion means may be employed. The side beams 1 of the truck are projected forwardly, as at 4 and 4^a to

properly support a shovel and conveyer hereinafter referred to.

Referring particularly to Figs. 2 and 6, on the underneath face of the ends of the projecting beams 4 there is mounted a U-shaped stirrup 5, one of which stirrups is provided for each beam, and the said stirrups straddles said beams 4 as shown in Fig. 6, and are securely bolted thereto by means of the bolts 6, in such manner as to leave a space or housing between the beams 4 and the bottom of the stirrup, which housing is adapted to contain the ends of a pair of brace bars, in the form of angle irons, to support the forward end of the shovel hereinafter referred to. As shown more particularly in Fig. 2, these brace bars or angle irons consist of a pair of flat members, the upper one of which has a horizontal arm 7 and a forward downwardly inclined arm 8 disposed at an angle coincident with the desired inclination of the shovel. The other brace or angle bar consists of a horizontal arm 9 bent downwardly, as at 10, and further bent, as at 11, at an angle parallel to the arm 8, the bent portion 12 between the positions 10 and 11 being spaced away and forming a trussing member opposite the bend 13 of the upper angle bar 7-8. The arms 7 and 9 of the angle bars are bolted or riveted together as at 14, and the inner end projected within the housing of the stirrup 5, and the downwardly inclining arm 8 of the upper angle bar is bolted or riveted, as at 15, to the bottom of the shovel before referred to. This shovel is one of the primary features of the invention in combination with proper propulsive and conveyer means, and the shovel consists of a bottom 16, having vertical side walls 17 which converge upwardly and inwardly, terminating in a horizontally disposed discharge plate 18, which discharge plate, in plan view, is in the nature of a right-angled triangle, the hypotenuse edge of which, 19, extends transversely across the conveyer hereinafter referred to, for an object which will be later described. The side wall 17 of the shovel, on one side terminates at the apex 20 of the triangular discharge plate 18, while the other side wall 17 of the shovel continues as at 21, forming a wall contiguous with the base of the triangular discharge plate 18, and extends transversely across the conveyer before referred to.

From the foregoing and the drawings, it will be clearly seen that the shovel is in the form of a scoop, the front edge 22 of which is of sufficient width to extend across the track 23 to be cleared, where the invention is used in connection with the clearing of a street railway or steam railroad track.

The conveyer, more clearly shown in Figs. 1 and 4, consists of side plates 24 having at each end a transverse roller 25, over which

passes a flexible belt 26, which may be provided on its outer surface with cross plates or blades 27. Between the side plates 24 are also arranged a plurality of rollers 28 on which the upper portion of the endless belt 26 rides. As shown more clearly in Fig. 4, this conveyer may be provided with a casing or cover 29, the rear wall of which extends adjacent the side sill or beam 4, but it and the lower end of the conveyer are so disposed with relation to the adjacent side sill that the conveyer may be swung upwardly in an arc that will allow it to pass by the side sill, when it is desired to swing the conveyer from its transverse position to a position longitudinal of the truck. The conveyer inclines upwardly at an angle sufficient to properly discharge the shoveled snow at a height above the level of the snow, and the upper end of the conveyer has its side walls pivotally mounted between the arms 30 of a clevis or bifurcated member, by means of the pivot pin or bolt 31. The clevis or bifurcated member is in turn pivotally mounted, by means of the pin 32, on the side beam 4 of the truck, so that a universal connection is provided between the conveyer and the supporting truck, whereby the conveyer may be elevated vertically to a horizontal position and then swung around horizontally on the pivot 32, to the position shown in dotted lines in Fig. 1. 33 designates a stud shaft mounted on the side wall 24 of the conveyer, as seen in Fig. 1, and 34 is a pintle carried on the end of the lower roller 25 of the conveyer. On this pintle 34 is rigidly mounted the sprocket wheel 35, and on the stud shaft 33 there is loosely mounted an idle sprocket wheel 36, said sprocket wheel 36 being provided with a clutch member 37 coöperating with a clutch member 38 carried by the end of a shaft 39, journaled on the truck and connected at its other end to a suitable motor 40, which is preferably operated independently of the main motor 3. 41 is a sprocket chain coöperating with the sprocket wheels 35 and 36, and 42 is a clutch lever for throwing the clutch members 37 and 38 into and out of clutch. 43 represents a pair of hangers, one on each side of the truck frame, and which hangers are slotted at their lower ends, as at 44, to receive pintles 45 of a rotatable brush 46 suspended by means of chains 47, the right hand pintle, 45, of the brush being provided with a sprocket wheel 46 connected by means of a sprocket chain 47, with a sprocket wheel 48 mounted on a shaft 49, suitably supported and geared to the motor 3. One of the brackets 43 is located in advance of the other, so that the rotary brush 46 is arranged diagonally of the truck and is designed to sweep the track clear of the snow located below the tread of the rails.

The clutch connection between the shaft 130

39 and the conveyer driving mechanism is merely shown diagrammatically, as are also the motor 40, for driving the conveyer, and the motor 3, for driving the truck, as various other constructions might be used, and the details of these features form no part of the present invention. It may also be stated that while the shaft 39 may be geared up to the main motor 3, instead of providing an independent motor 40, still it is desirable to provide a separate motor 40 in order that the speed of the conveyer may be regulated relatively to the travel of the truck and shovel, and, as a matter of fact, the conveyer is driven much more rapidly than the advancing shovel, and by the arrangement shown is driven quite independently of the main motor.

From the foregoing description and from the drawings, it is believed that the operation of my improved track cleaner is obvious, but it might briefly be stated that upon the advance of the machine the snow is forced up the inclined shovel onto the triangular discharge plate 18, the discharge edge of which extends diagonally across the conveyer from one side of the shovel to the other side thereof, and by this means the advancing ribbon or sheet of snow is caused to begin to discharge at the right hand side of the machine at the position 20 in advance of the discharge from the left hand side of the machine at the position 21^a, so that the advancing snow is evenly distributed upon the conveyer clear across the same, preventing the snow from being banked up in one position thereon. The endless conveyer being operated at a speed considerably greater than the movement of the advancing machine, the snow is quickly and readily conveyed and discharged at the right hand side of the machine, a considerable distance clear of the track, and the rotary brush 46 sweeps clean the roadway below the position of the front edge 22 of the shovel.

I am aware of the fact that a number of snow plows have been invented, which are designed to clear tracks, with the same broad aim in view as the present invention, but my invention does not consist of a snow plow but is believed to be a new departure whereby means are provided for shoveling off the snow by an actual shoveling process, whereby each shovel full, as it were, is thrown on

the conveyer and discharged at the side of 55 the machine, so that at no time is there any great obstruction to the advance of the machine through the snow.

Having thus described the invention, what I claim is:

1. In a machine of the character described, including a supporting vehicle, means for driving said vehicle, and an upwardly inclined endless belt conveyer disposed transversely of said vehicle and terminating beyond the side thereof; the combination of an upwardly inclined shovel, comprising a flat uncovered shovel blade, terminating at its upper end in a horizontally disposed triangular shelf, forming an integral continuation of 70 said shovel blade, and having a rearwardly disposed diagonal discharge edge extending from one side of the shovel to the other side thereof, and extending entirely across the lower end of said conveyer, the whole providing an uncovered, uninterrupted and unobstructed passageway for the ascending shoveled snow; and means for driving said conveyer, substantially as described.

2. In a machine of the character described, including a supporting vehicle, means for driving said vehicle, and an upwardly inclined endless belt conveyer disposed transversely of said vehicle and terminating beyond the side thereof; the combination of an upwardly inclined, rigidly supported, flat shovel blade, provided with vertical side walls, an open upper end, and an open top for its entire length, said flat shovel blade terminating in a triangular-shaped horizontal shelf formed integrally therewith and having a rearwardly disposed discharge edge extending diagonally from one side of the shovel blade to the other side thereof and entirely across the lower end of said conveyer, and said vertical side walls extending to the respective ends of the diagonal edge of said discharge shelf, the whole forming an uncovered, uninterrupted and unobstructed passageway for the ascending 100 shoveled snow; and means for driving said conveyer, substantially as described.

In testimony whereof, I affix my signature, in presence of two witnesses.

CHARLES SCHEIDEN.
